UNITED STATES PATENT OFFICE.

AUGUST SUNDH, OF YONKERS, NEW YORK, ASSIGNOR TO OTIS ELEVATOR COMPANY, A CORPORATION OF NEW JERSEY.

HOISTING-GEAR FOR ELEVATORS.

SPECIFICATION forming part of Letters Patent No. 757,788, dated April 19, 1904.

Application filed July 31, 1903. Serial No. 187,747. (No model.)

To all whom it may concern:

Be it known that I, AUGUST SUNDH, of Yonkers, Westchester county, New York, have invented a new and useful Improvement in 5 Hoisting-Gear for Elevators, of which the following is a specification.

The invention relates to frictional hoisting-gear for elevators.

The invention relates to a hoisting-gear actuated through frictional contact and means for varying said frictional contact correspondingly to and controlled by the load.

The invention consists in the construction and combinations of parts hereinafter more particularly set forth.

In the accompanying drawings, Figure 1 is a general view showing the car, counterweight, and hoisting-gear, the latter being in section on the line $x-x$ of Fig. 2. Fig. 2 is a similar 20 view in side elevation showing also the actuating electric motor. Fig. 3 shows the hoisting-gear in cross-section on the line $y-y$ of Fig. 1. Fig. 4 is a front elevation, and Fig. 5 a top view, of the hoisting-gear, drawn on a larger scale than appears in the preceding figures.

Similar letters and numbers of reference indicate like parts.

Referring first to Figs. 1 and 2, A is the 30 car, and B the counterweight connected thereto by the cable C, passing over the fixed pulleys D E. An electric motor F is supported on suitable standards G on the bed-plate H. The armature-shaft of said motor carries a 35 pulley I, by which the friction hoisting-gear now to be described is actuated. On the bed-plate H is a lug 1, through which passes the pivot-shaft 2. Said shaft carries two pairs of arms 3 4 and 5 6. Journaled in the upper 40 ends of arms 3 4 is the shaft 7 of drum 8, and journaled in the upper ends of arms 5 6 is the shaft 9 of drum 10. The pairs of arms swing on a common pivot-shaft 2. The extent of their outward movement may be limited by 45 the adjustable screw-stops 11 12, which enter the bed-plate and against which said arms may bear. Each drum 8 and 10 has at each end a smooth circular periphery 13 and between said smooth portions a circumferentially-grooved

portion. The motor-pulley I is elongated and 50 also has at each end a smooth circular periphery 14 and between said smooth portions a depressed portion 15. The pulley I lies between the drums 8 and 10 and above the drum-centers with its smooth peripherical portions 14 in 55 frictional contact with the smooth peripherical portions 13 of both of said drums 8 and 10. On each arm 3 4 and 5 6 are two lugs 16, carrying rollers 17 and 17, which extend between the pairs of arms and serve as guides for the 60 cable on the drums, as hereinafter described. Finally, on the outer sides of said arms 3 4 5 6 are lugs 18, and through the lugs on the opposite arms of the respective pairs pass loose bolts 19. A helical spring 20 extends between the head of each bolt and one lug 18, which lug thus forms an abutment for said spring. The other end of the bolt after passing through the opposite lug 18 is threaded to receive adjusting-nuts 21. By means of 70 said nuts and spring the pairs of arms may be drawn together, so that the drums 8 and 10 may thus be caused to exert a predetermined initial pressure on the periphery of driving-pulley I.

The cable C after being connected to the car A is carried over fixed pulleys D and then around the grooves in drums 8 and 10 to fill said grooves, passing between the rollers 17 and 17 and then over fixed pulley E to the 80 counterweight B. It will be obvious that the strain on the cable due to the weight of car and counterpoise operates to close the drums 8 and 10 together, or, in other words, to press them into frictional contact with pulley I. 85 The motor being set in rotation, motion is communicated from pulley I to said drums and the elevator-car raised or lowered in accordance with the direction of said rotation. It will further be noted that any increase in 90 the load in the car will be exerted in like manner to force the drums together and so to augment their pressure upon said pulley I, while any decrease of the load will permit them to move asunder, thus diminishing said pressure. 95 The result, therefore, is that by means of this device the frictional engagement of the motor with the load depends directly upon the magni-

tude of said load, becoming greater as the load increases, but at all times automatically adjusting itself to whatever the actual condition of load may be. The motor is geared to the drums without intermediate mechanism and is supported on the same bed-plate as the hoisting-gear.

I claim—

1. In a hoisting-gear, a rotary pulley, two hoisting-drums in frictional contact therewith, swinging supports for said drums and a cable adapted to be connected to the load and extending around said drums.
2. In a hoisting-gear, a rotary pulley, two hoisting-drums in frictional contact therewith, supports for said drums swinging on a common axis and a cable adapted to be connected to the load and extending around said drums.
3. In a hoisting-gear, a rotary pulley, two hoisting-drums in frictional contact therewith, supports for said drums swinging on a common axis located below said drums and a cable adapted to be connected to the load and extending around said drums.
4. In a hoisting-gear, a rotary pulley, two hoisting-drums in frictional contact therewith, swinging supports for said drums, means for regulating the extent of movement of said supports from said pulley and a cable adapted to be connected to the load and extending around said drums.
5. In a hoisting-gear, a rotary pulley, two

hoisting-drums in frictional contact therewith, swinging supports for said drums, means acting upon said supports to regulate said frictional contact and a cable adapted to be connected to the load and extending around said drums.

6. In a hoisting-gear, two hoisting-drums, a cable adapted to be connected to the load and extending around both, a toggle-support for said drums and a rotary pulley interposed between and in frictional contact with said drums.

7. In a hoisting-gear, a rotary pulley, two movably-supported hoisting-drums having their axes below the axis of said pulley, means for raising said drums into frictional contact with said pulley and a cable adapted to be connected to the load and extending around said drums.

8. In a hoisting-gear, a rotary pulley, two hoisting-drums having their axes below the axis of said pulley, means for swinging said drums upward and into frictional contact with said pulley and a cable adapted to be connected to the load and extending around said drums.

In testimony whereof I have signed my name to this specification in the presence of two subscribing witnesses.

AUGUST SUNDH.
